United States Patent Office

Des. 192,708
Patented May 1, 1962

192,708

JUG

Thomas L. Cory, Independence, Mo., assignor to Owens
Plastics Company, Kansas City, Mo., a corporation of
Missouri

Filed Sept. 20, 1961, Ser. No. 66,773

Term of patent 14 years

(Cl. D58—5)

Fig. 1.

Fig. 2.

Fig. 3.

FIG. 1 is a side elevational view of a jug, embodying my new design;

FIG. 2 is a rear elevational view thereof; and

FIG. 3 is a top plan view thereof.

I claim:

The ornamental design for a jug, substantially as shown.
